UNITED STATES PATENT OFFICE

HENRY M. CROUSE, OF CHICAGO, ILLINOIS

CARD INDEX REFERENCE HOLDER

Application filed June 13, 1929. Serial No. 370,478.

The invention is in a card index reference holder.

The primary object of the invention is to provide a simple holder device for the orderly arrangement of a loose leaf type pack of cards or papers, such device to involve structure for permitting easy and quick removal of any selected card from its place in the pack, and of course, also, return of the card to its proper place.

Another object is to provide in a holder having holder posts and cooperating closure elements, a lever controlled mechanism for snapping said elements open or shut as desired.

Other objects will appear as the disclosure is made.

Briefly, such objects are achieved in an illustrative form of the invention herein disclosed, by providing a body in which is carried a centrally disposed transverse shaft which pivotally connects two card holder sections. One section mounts posts upon which loose leaf cards or the like are arranged, and the other section mounts cooperating hook-shaped closure elements. The posts and closure elements are adapted to form closed loops to permit transfer of the cards from one section to the other. One of the sections at its end is, additionally, pivotally carried on a transverse shaft at the end of the body. The central, or middle shaft already mentioned, is bodily movable up or down, in slotted ways in the body, by means of a lever. When said lever is pressed down, the middle shaft moves bodily up, with the inner ends of the two holder sections. When an over-center point is reached in this up movement, springs are active to snap the sections upwardly and yieldingly hold the closure elements open to permit removal of any pre-selected card, all as will later more fully appear.

In the accompanying sheets of drawings illustrating a practicable form and modification of the invention:

Figure 1 is a general, side elevational view of the improved holder;

Figure 2 is a similar view, partly in section as would be seen along the line 2-2 appear-

ing in Figure 4, when looking in the direction of the arrows;

Figure 3 is an end, central, sectional view as seen along line 3-3 of Figure 1, looking with the arrows;

Figure 4 is a plan view;

Figure 5 is a cross sectional view, looking at an end of the holder, from the top and showing a modification; and,

Figure 6 is a similar view showing a preferred structure as shown in Figure 2.

The body of the device appears at 10 and includes two side walls 11, an end wall 12, and another end wall 13. In transverse alignment, and intermediately of the ends of the holder, the side walls 11 are provided with slots 14 in which is mounted a transverse shaft 15 having one end projected slightly laterally of a side wall as shown in Figure 3. The same wall 11 carries a fulcrum pin 16 for pivotally mounting a hand lever 17, intermediately of its ends, as best appears in Figure 1. The end of the lever 17 is formed with a slot 18 in which is arranged the projected end of the shaft 15. It can now be seen that when a user presses down on the lever, it will cause the shaft to be bodily raised in its slotted ways.

A first holder section is shown at 19 provided with a pair of spaced, upright posts 20 adapted to carry a pack of loose leaf cards, or the like, generally indicated at 21. This holder section 19 has depending side flanges 22 as shown best in Figure 2 which at the center of the body are pivotally hinged to the central cross shaft 15; while at the opposite end of the section, these side flanges 22 are pivotally connected to a second cross shaft 23 mounted in the end of the body side walls 11.

A second holder section 24 is also provided, of similar construction, having an end, depending flange 25, and being, at its inner end, also hingedly or pivotally connected to the middle shaft 15. This section 24 is provided with a pair of hook-shaped, closure elements 26 which cooperate with the posts 20 on the other section 19 to form separable, closed loops for the transfer of the loose leaf cards from one section to the other as will be ready-

ly understood. A pair of spaced, horizontal guide rods 27 are provided as supports for the free end of the section 24 as appears best in Figures 2, 3 and 6. These rods are fixed in the end wall 13 of the body and are supported by vertical extensions, at their inner ends, mounted in any suitable manner in the floor of the body 10. Coil springs 28 encircle the horizontal run of these rods between the end 10 25 of the holder section 24 and the adjacent end wall 13 of the body.

As appears in Figure 2, it will be seen that the center shaft 15 lies lower than the end shaft 23 and horizontal guides 27. Thus, 15 with the springs 28 exerting a push force on the end of the section 24 the tendency is to keep the hinged sections 19, 24, down as the shaft 15 is below center. This keeps the posts 20 and closure elements 26 as closed loops. If now, the lever 17 is pressed down to raise the shaft 15 above dead center the springs 28 exert a force that will open the loops by separating the posts and closure elements, because the two sections 19, 24 tilt 20 upwardly at their hinged connection to the bodily raisable shaft 15. These springs 28 are concealed by a cover plate 29 shown in Figure 2.

In Figure 5 a modification of the spring structure is illustrated in which a single spring 28' is provided. The spring is, in this case, a pull spring, and connects underneath the section 24, between the end wall 25' and a bracket or anchor 30. The guide rods 27' are retained for the sliding movement of the flange 25'. This form may be preferred as it is simpler and permits use of a shorter body. Therefore, it has the advantage of compactness.

40 In practice, loose leaf index cards or leaflets are stored on the holder posts 20 of the section 19. In the normal position of the parts as shown in the full lines in Figure 2, the cards may be transferred across the loops 45 formed by the closure elements 26 to the other section 24 for the purpose of turning up any selected card. If it is now desired temporarily, to remove said card from the stack, the user presses down on the hand lever 17 which 50 bodily raises the shaft 15 to tilt the hinged inner ends of the holder sections upwardly to the dotted line showing in Figure 2, which then causes the posts and closure elements to 55 separate in the manner indicated, thus permitting removal of said selected card. The springs function to lock, yieldingly, the parts in open or closed position because of the over and under dead center positions made possible for the hinge shaft 15 by the provision of 60 its slotted way mounting in the body sides.

From this detailed disclosure it must now be readily appreciated that an improved structure for a card index reference holder has been provided, which achieves all of the desirable objects heretofore recited.

It is the intention to cover all such immaterial changes and modifications of the illustrative forms of the structure herein shown, as do not depart from the spirit and scope of my invention, as is indicated by the definitions contained in the appended claims. 70

What I claim is:

1. In a file holder, a body, a first holder section in the body provided with posts to hold a loose leaf card pack, a second holder section in the body provided with closure elements for the posts, a shaft pivotally connecting the two sections, and means for bodily raising and lowering the shaft and adjacent ends of the connected sections to open or close the closure elements relative to the posts. 75

2. In a file holder, a body, a first holder section in the body provided with posts to hold a loose leaf card pack, a second holder section in the body provided with closure elements for the posts, a shaft pivotally connecting the two sections, and a lever pivotally mounted on the body and connected to said shaft for bodily raising the same to cause the closure elements to open relative to the posts. 80

3. In a file holder, a body, a first holder section in the body provided with posts to hold a loose leaf card pack, a second holder section in the body provided with closure elements for the posts, a shaft pivotally connecting the two sections, a lever on the body and connected to the shaft to raise the same for opening the closure elements relative to the posts, and yielding means for maintaining the closure elements in open position. 95

4. In a file holder, a body, a shaft arranged centrally across the body, a first holder section having its outer end pivotally connected to one end of the body, a second holder section, said sections having adjacent inner ends connected to said shaft, cooperative posts and closure elements on the sections to form loops for carrying loose leaves which may be transferred from one section to the other, means pivotally carried outside the body for raising the shaft and inner adjacent ends of the sections to open the closure elements, and means to retain the closure elements in open position. 100

5. In a file holder, a body, hingedly connected holder sections mounted therein, separable file holder posts and closure elements on the holder sections, and lever means carried on the body and having connection with the sections for tilting the inner adjacent ends of the said sections upwardly to separate the posts and closure elements. 110

6. In a file holder, a body, file holder sections having their inner adjacent ends hingedly connected together and mounted on the body, cooperative file holder posts and closure elements on the said sections, lever means carried on the body and having connection with the sections for tilting the said sections 115 120 125 130

upwardly at their hinged connection to separate the posts and closure elements, and means exerting a force to keep the closure elements in open position.

6 7. In a file holder, a body, a pair of file holder sections having their inner adjacent ends hingedly connected together at the center of the body, one of said sections having an end pivotally connected to an end of the 10 body, the other section having an end carried in the body for sliding movement, co-operable and separable leaf-retainer elements on the sections, means to raise the hinge connection between the sections to tilt said 15 sections for separating the retainer elements, said hinge comprising an over dead center lock, and yielding means for holding the hinge over dead center.

8. In a file holder, a body having end walls 20 and side walls, the latter having oppositely arranged slots formed therein, a cross shaft journaled in said slots, a pair of holder sections in the body and having adjacent inner ends connected to the shaft, cooperating 25 posts and closure elements therefor on the said sections, a lever on a side wall of the body and connected to an end of the shaft to raise the same in the slots to tilt the holder sections and thereby open the closure elements relative to the posts, and spring means 30 in the body acting on one end of a holder section to yieldingly retain the closure elements in their open positions.

9. In a file holder, a body having end walls 35 and side walls, a pair of hingedly connected holder sections arranged in the body, one of the sections having a pivotal connection at one end to an end of the body, the other section having its free end slidably mounted at 40 the other end of the body, separable means on the sections for holding loose leaves, means on a side wall for engaging the inner adjacent hingedly connected ends of the holder sections to tilt the same upwardly to thereby 45 open the separable means, and spring means acting on the slidably mounted end of one of the holder sections to retain the separable means open.

10. In a file holder, a body, hingedly connected holder sections mounted therein, separable file holder posts and closure elements on the holder sections, means for raising the hinged connection to tilt the sections thereby causing the closure elements to separate 55 from the posts, and spring means beneath one of the sections pulling on an end thereof to yieldingly retain the sections tilted with the closure elements in open position.

11. In a file holder, a body, a first holder 60 section in the body provided with posts to hold a loose leaf card pack, a second holder section in the body provided with closure elements for the posts, a shaft pivotally connecting the two sections, means mounting the 65 shaft in the body for bodily floating up and

down movement with the adjoining ends of said sections to open or close the closure elements relative to the posts, and means carried by the body for raising or lowering the shaft.

12. In a file holder, a body, a shaft arranged centrally across the body in vertical slots formed in said body, a first holder section having its outer end pivotally connected to one end of the body, a second holder section, said sections having adjacent inner ends connected to said shaft, cooperative posts and closure elements on the sections to form loops for carrying loose leaves which may be transferred from one section to the other, lever means pivoted to the outside of the body and having a connection for raising the shaft in said slots with the inner adjacent ends of the sections to open the closure elements, and spring means acting on one of the sections to keep the closure elements open.
